UNITED STATES PATENT OFFICE.

CHARLES KINGSTON WELCH, OF COVENTRY, ENGLAND, ASSIGNOR TO THE PNEUMATIC TYRE COMPANY, LIMITED, OF DUBLIN, IRELAND.

DESIGN FOR A WHEEL-RIM.

SPECIFICATION forming part of Design No. 25,997, dated September 8, 1896.

Application filed July 19, 1895. Serial No. 556,514. Term of patent 14 years. Registered in England December 9, 1892, No. 22,669; in Switzerland August 31, 1894, No. 9,201; in Spain October 19, 1894, No. 16,257; in South Australia January 4, 1895, No. 2,848, and in New Zealand January 5, 1895, No. 7,363.

To all whom it may concern:

Be it known that I, CHARLES KINGSTON WELCH, engineer, a subject of the Queen of Great Britain, and a resident of Coventry, England, have invented and produced a new and original Design for Wheel-Rims, (for which patents have been obtained in Great Britain, No. 22,669, application date December 9, 1892; in Spain, No. 16,257, issued October 19, 1894; in Switzerland, No. 9,201, application date August 31, 1894; in South Australia, No. 2,848, application date January 4, 1895, and in New Zealand, No. 7,363, application date January 5, 1895,) of which the following is a specification, reference being had to the accompanying drawings, forming part thereof.

Figure 1 of the drawings shows an enlarged view of a part in cross-section of a circular wheel-rim or wheel-tire rim shaped in conformity with my design. Fig. 2 shows a plan or elevation view, on a smaller scale, of the

complete rim. Fig. 3 shows an edge view of the same.

A A are grooves, with rounded corners, in the base B of the rim, between which grooves rises the projection or rib C. From the base project radially the slightly-flaring side walls or flanges D, which have the rounded corners E and the outwardly-turned and rounded edges F.

The essential features are the grooves in the rim and the flanges with their curved edges.

What is claimed as new is—

The design for a wheel-rim, substantially as shown and described.

In witness whereof I have hereunto set my hand this 19th day of June, 1895.

CHARLES KINGSTON WELCH.

Witnesses:

P. H. BUDGEN,
FRED C. HARRIS.
